UNITED STATES PATENT OFFICE

2,513,631

PAIL HOLDER

Herbert C. Erickson, Minneapolis, Minn.

Application May 14, 1947, Serial No. 748,141

1 Claim. (Cl. 248—154)

1

This invention relates to pail holders.

It is an object of my invention to provide a simple but highly efficient pail holder which is adapted to be attached to a flat surface and which will hold a pail securely embraced therein.

More specifically, it is an object of my invention to provide a pail holder having a split annulus which has a toggle take-up link connecting the two ends, whereby easy reception of the lower portion of a pail therein is permitted when said toggle link is in open position, and whereby said annulus tightly embraces said pail to securely hold the same when said toggle link is in closed position, said holder structure being adapted to be attached to a flat surface.

It is a further object of my invention to provide a pail holder having a split annulus and means whereby the tension in said annulus and the "take-up" therein when tightened is equally distributed throughout its entire length.

These and other objects and advantages of my invention will be more apparent from the following description made in connection with the accompanying drawings, wherein like reference characters refer to similar parts throughout the several views and in which:

Figure 1 is a top plan view of my pail holder with the lower portion of a pail retained therein, the upper portion of said pail being removed;

Figure 2 is a side elevational view of the structure shown in Figure 1; and

Figure 3 is a vertical sectional view taken substantially along the line 3—3 of Figure 1, showing the toggle take-up link in detail.

As shown in the accompanying sketches, I provide a pail holder designated as an entirety by the letter A and having a split annulus 5, one end of which has a hook 6 formed therein by doubling back the end portion of said annulus 5 upon itself; the other end portion of said annulus 5 being disposed in open spaced relation to the hook 6 is also doubled back upon itself to receive a connector link 7, said connector link 7 being secured therein in pivotal relation thereto by rivets 8 through the two overlapped thicknesses of the annulus 5. A protector plate 9 having its end portion underlying the second mentioned end of annulus 5 is also connected thereto by the rivets 8.

A connector link 10 has a vertically disposed outer face 10a and a pair of flanges 10b disposed at right angles to said face 10a, one end of each of said flanges being curved to form bearing surfaces 11 which are adapted to ride smoothly on

2

the outer surface of protector plate 9. The link 7 is pivotally connected to the flanges 10b substantially adjacent the outer face 10a of toggle link 10, and also is disposed substantially adjacent the curved bearing ends 11 of said toggle link 10, the longitudinal arms of link 7 being disposed between said flanges 10b.

A second connector link 12 is pivotally connected to the flanges 10b and this connection is disposed substantially adjacent the inner edges of said flanges 10b and a slight distance rearwardly from the curved bearing ends 11 of said flanges, the arms of said link 12 being disposed outwardly of said flanges 10b. The free end of link 12 is adapted to be releasably received by the hook 6 on the free end of annulus 5.

An attachment base is formed by the straps 13, 14 and 15 pivotally connected at their inner ends, which pivotal connection 16 is disposed substantially adjacent the center of annulus 5. The straps 13, 14 and 15 have upstanding arms 13a, 14a and 15a, respectively. These arms 13a, 14a and 15a are all fixed, as by rivets 17, to the annulus 5 in peripherally spaced relationship to each other. Each of said straps has an attachment aperture 13b, 14b and 15b, formed in the horizontal portion thereof, the attachment apertures 14b and 15b being elongated to permit said straps 14 and 15 to slide on a screw or bolt through said apertures.

The protector plate 9 underlies the toggle link 10 when in closed position, as shown in the accompanying drawings, and the bearing ends 11 ride thereon, the inner edges of the flanges 10b engaging thereagainst as best shown in Figures 1 and 3.

The straps 13, 14 and 15 are initially attached to any flat surface such as the running board of an automobile or the trunk floor or even the floor 40 of a trailer. The screws or bolts through the elongated apertures 14b and 15b permit respective straps 14 and 15 to swing although holding said straps against the flat surface.

With the toggle link 10 in open position and the connector link 12 removed from the hook 6, a pail such as the pail 18 is inserted into the annulus 5 with the bottom of said pail engaging against the top surfaces of straps 13, 14 and 15. The link 12 then has its free end hooked into the hook 6 and the toggle link is then swung on its pivotal connection with link 7, the bearing ends 11 riding against the protector plate 9. During this swinging operation of the toggle take-up link 10 the pivotal connection with connector link 12 follows an arcuate path around the pivotal con-

nection with link 7 and ultimately is disposed inwardly of said pivotal connection with link 7 when toggle link 10 is in completely closed position. This over-center action provides a positively locked take-up connection and is very efficient for this type of device.

During this closing operation the annulus 5 has its ends pulled together a substantial distance so that its inner periphery tightly embraces the outer periphery of the pail 18. As the ends of the annulus 5 are pulled together it will be seen that there will be a displacement on each side of the rear strap 13 of the portions of the annulus 5 at the points where the upstanding arms 14a and 15a are fixed thereto. By providing the pivotal joint 16 at the center and the elongated slots 14b and 15b it will be seen that the straps 14 and 15 will be freely permitted to follow said displacement without producing any appreciable stress in either the straps 14 and 15 or in the annulus 5. By this freedom of movement the tension in annulus 5 as well as the amount of displacement throughout its length will be substantially equalized.

It will be seen that I have provided a highly efficient, extremely simple pail holder which is particularly adapted for securely holding minnow pails and the like while in transit and which due to the equalized tension in annulus 5 will not bend said pail out of shape. The protector plate 9 prevents the bearing ends 11 from riding directly on the side of the pail and thus protects the pail from undue wear. The release toggle link mechanism herein provided is particularly adapted to this use, as is obvious from the foregoing description. It provides a positively locking take-up structure which will securely hold during even the severe vibrations of an automobile or trailer traveling over a rough road while

at the same time providing easy entrance of a pail into said annulus, making the connection operation quick and simple.

It will, of course, be understood that various changes may be made in the form, details, arrangement and proportions of the parts without departing from the scope of my invention.

What I claim is:

A pail holder having in combination a split annulus; a toggle take-up link adapted to connect the ends of said annulus, a base comprising a plurality of strap elements having their inner ends pivotally interconnected substantially at the center of said annulus, the diverging angles between said strap elements being substantially equal, and upstanding elements fixed at one end to said annulus in equally spaced relation around the periphery thereof and fixed at the other end to said straps, said pivotal connection between said strap elements permitting certain of said straps and upstanding elements to shift when said toggle link is taken up to tightly clamp said annulus about a pail; and means for attaching said strap elements to a flat surface to securely hold down said pail and exert substantially equally distributed hold down force on the periphery of said annulus when clamped about a pail.

HERBERT C. ERICKSON.
